(57) **CLAIM**

I/We claim the ornamental design for a snow moving apparatus, as shown and described.

DESCRIPTION

FIG. 1 is a front perspective view of the snow moving apparatus;

FIG. 2 is a rear perspective view of the snow moving apparatus;

FIG. 3 is a front elevational view of the snow moving apparatus;

FIG. 4 is a rear elevational view of the snow moving apparatus;

FIG. 5 is a bottom plan view of the snow moving apparatus;

FIG. 6 is a top plan view of the snow moving apparatus;

FIG. 7 is a left side view of the snow moving apparatus; and,

FIG. 8 is a right side view of the snow moving apparatus. The broken line showing of is for illustrative purposes only and forms no part of the claimed design. The blade portion of the claimed design is shown broken-away do to indeterminate length.
